UNITED STATES PATENT OFFICE.

DANIEL HURLEY, OF PROVIDENCE, RHODE ISLAND, AND JOHN EDMUND O'SHEA, OF NEW YORK, N. Y.

DRYING APPARATUS.

946,843.

Specification of Letters Patent. Patented Jan. 18, 1910.

Application filed April 10, 1908. Serial No. 426,381.

To all whom it may concern:

Be it known that we, DANIEL HURLEY, of Providence, in the county of Providence and State of Rhode Island, and JOHN EDMUND O'SHEA, of New York, in the county of New York and State of New York, have invented certain new and useful Improvements in Drying Apparatus; and we do hereby declare the following to be a full, clear, and exact description of the invention, such as will enable others skilled in the art to which it appertains to make and use the same.

This invention relates to vacuum drying apparatus especially designed for drying rubber, rubber covered wire, coils, cables, armatures, etc.

The invention is directed to providing improved means, rigid in construction, and accessible in operation, for drying in the presence of a vacuum by the application of heat, and for automatically controlling the vacuum and the circulation of steam or other heating fluid, thereby maintaining absolute dryness without overheating the material.

A further object of the invention is to provide improved drying shelves and to so support them as to permit their free expansion independent of the expansion of the casing.

In the accompanying drawings Figure 1 is a front elevation, and partial section through the line A—B, Fig. 2. Fig. 2 is a plan view partly broken away. Fig. 3 is a front elevation showing a slight modification.

Referring to the drawings, 1 designates an inclosing tank and 2 the cylindrical wall thereof although any desired form of casing may be used.

3 represents the chambered heating shelves shown transversely disposed in the casing in series communication and mounted on ledges 4. Each of these shelves is shown comprising upper and lower spaced apart plates 5 and end pieces 6 projecting beyond the plates and resting freely upon the ledges 4. By this means an effective support is provided while permitting the shelves to freely expand and contract. This arrangement of the shelves provides for readily removing or repairing one plate independently of the others and for the grouping of the shelves so a smaller number may be operated when desired.

We provide for a circulation of steam or other heating and drying fluid through the

shelves. For this purpose an inlet pipe 7 is shown entering the casing above the top of the superposed series of shelves. This pipe is in communication with the top shelf at 8 as shown in Fig. 1 and the shelves are connected by tubes 9, preferably swiveled or pivotally connected to the shelves to allow of unequal expansion, the inlet to the respective shelves being at one side and the outlet therefrom at the other. A partition 9a extends from one end to near the other end of each shelf, as shown in Fig. 2, or between the inlet and outlet, thereby providing means for guiding the elastic heating fluid in its path through the shelf so that the temperature at the plate may be equal throughout its surface. Thus the steam admitted to the shelf at 8 from pipe 7 will pass to the other end of the shelf and then back and through tube 9 to the next subjacent shelf where the described course is repeated, the path of the steam being such that it drains the shelves of deposits, water and drips. After passing through the lowermost shelf the steam leaves the casing through pipe 10 in which is a pressure regulator 12 which automatically controls the pressure and flow in the heating shelves without acting as a vacuum breaker.

The space within the casing surrounding the shelves constitutes a vacuum chamber 13 from which a pipe 14 leads to a vacuum pump 15, a pressure controlling valve 16 being shown arranged in the pipe 14. This valve when in action automatically controls the pressure in the vacuum chamber 13 while maintaining the vacuum. Through pipe 17 communication is established from regulator 12 to pipe 14 and the pump. The vacuum controlling valve 16 comprises a valve 18 on a stem 19 extending up through the casing 20 and under the influence of a coil spring 21 encircling the stem and a diaphragm 22 arranged within the casing and secured to the stem. The office of this valve is that when the pump 15 is set in operation and the desired vacuum is established in the casing the vacuum acting on the diaphragm 22 which has atmospheric pressure on its upper side seats the valve 18 as against the tension of coil spring 21. The valve remains closed while the desired vacuum is maintained but when the vacuum in chamber 13 lessens sufficiently for the spring to overcome its load the valve is unseated and passage through the valve is unseated and passage through 110

pipe 14 to the vacuum pump 15 is established until the desired vacuum in chamber 13 is again created. This action may continue indefinitely without destroying or 5 breaking the vacuum in the chamber 13.

We have shown a condenser 23 interposed in pipe 14 and provided with tubes 24 through which cooling water may circulate.

In the construction shown in Fig. 3 the 10 condenser is dispensed with and pipes 14 and 17 are shown leading to a rotary pump 25, the steam exhausting to the atmosphere at 26.

In operation the materials to be dried are 15 placed in pans on shelves 3 through the open ends of the casing, doors 27, Fig. 2, affording means of ready access. The vacuum pump is started and the pressure reduced in the casing to the desired operating vacuum, the 20 action of the regulator 16 maintaining the vacuum in chamber 13 as described. The steam supply is admitted through pipe 7 and after passing downwardly through the successive shelves it is exhausted through pipes 25 10 and 17 and regulator 12. This regulator, when adjusted according to conditions, automatically controls the flow of steam through the shelves thereby insuring its full heating effect. The vacuum pump exhausts 30 the vapor from chamber 13 while the regulator 16 maintains the pressure constant. The pump further withdraws steam from the shelves thus promoting the flow thereof while the regulator 12 controls the quantity 35 of flow.

We have specified the part 23 as a condenser since it is available for use in condensing the steam from the shelves and the vapors from the vacuum chamber, but it is 40 obvious that the heat of the water passing through its tubes 24 may be utilized in various ways, as for heating feed water.

We claim as our invention:—

1. In a drying apparatus, a casing, drying shelves therein, means for conducting drying fluid to and from said shelves, a pump, and connections between said pump 45

and the interior of said casing and between said pump and the outlet from said shelves, for the purpose stated.

2. In a drying apparatus, a casing, drying shelves therein, means for conducting drying fluid to said shelves, an outlet from said shelves, a pump, a pipe leading from said casing to said pump, a pressure regulator therein, a second pipe leading from said outlet to said pump, and a pressure regulator in said second pipe. 55

3. In a drying apparatus, a casing, drying shelves therein, means for conducting steam to said shelves, a pump for exhausting steam from, said shelves, a pipe leading from said casing to said pump and in communication with the steam exhaust from said shelves, and a condenser in said pipe. 60

4. In a drying apparatus, the combination with the casing having interior ledges, of a plurality of hollow drying shelves resting freely on said ledges and out of contact with said casing to allow of expansion, and 70 in series communication, each of said shelves having a heating fluid inlet and outlet at one end and a central partition extending from such end toward the opposite end, and means for conducting heating fluid through 75 said shelves.

5. In a drying apparatus, the combination with the casing having on the inner faces of its opposite walls a series of ledges, hollow drying shelves within said casing and resting freely on said ledges, and swiveled tubes connecting said shelves in series. 80

In testimony whereof, we have each signed this specification in the presence of two subscribing witnesses.
